CLAIM

The ornamental design for an aquarium, as shown and described.

DESCRIPTION

FIG. 1 is a front elevational view of an aquarium showing my new design, the rear being the same as the front shown;
FIG. 2 is a perspective view thereof;
FIG. 3 is a top plan view thereof; and,
FIG. 4 is a side elevational view thereof; the opposite side being the same as the side shown.

1 Claim, 3 Drawing Sheets

FIG. 1

FIG. 2

FIG. 3

FIG. 4
